UNITED STATES PATENT OFFICE.

LEONIDAS H. CRESS, OF WEST NEWTON, MASSACHUSETTS, ASSIGNOR TO FEDERAL TOOL COMPANY, OF EVERETT, MASSACHUSETTS, A CORPORATION OF MASSACHUSETTS.

DESIGN FOR A KNIFE.

42,620.

Specification for Design.

Patented June 18, 1912.

Application filed February 17, 1912. Serial No. 678,372. Term of patent 7 years.

To all whom it may concern:

Be it known that I, LEONIDAS H. CRESS, a citizen of the United States, residing in West Newton, in the county of Middlesex and State of Massachusetts, have invented a new, original, and ornamental Design for Knives, of which the following is a specification, reference being had to the accompanying drawing, forming part thereof.

The drawing is a perspective view of a knife showing my new design.

I claim—

The ornamental design for a knife as shown.

LEONIDAS H. CRESS.
